United States Patent Office

Des. 211,983
Patented Aug. 20, 1968

211,983

CHAIR

Dennis J. Kilper, 1104 W. Pratt St.,
Chicago, Ill. 60626

Filed Sept. 7, 1967, Ser. No. 8,510

Term of patent 14 years

(Cl. D15—1)

FIG. 1

FIG. 2

FIG. 3

FIG. 4

I claim:

The ornamental design for a chair, as shown.
